UNITED STATES PATENT OFFICE.

FORREST E. GILMORE, OF TULSA, OKLAHOMA.

FLUID-PRESSURE PUMP.

Application filed January 26, 1928. Serial No. 249,638.

This invention relates to a fluid pressure pump adapted for use in oil wells.

An object of the invention is the provision of a fluid pressure pump having a pair of balanced valves forming inlet and discharge valves for a fluid under pressure which is adapted to force the liquid from the well through a separate discharge pipe, means being actuated by the rise and fall of liquid for causing alternate actuation of the inlet and discharge valves.

Another object of the invention is the provision of a fluid pressure pump in which a tube supports a plurality of valves, with pairs of the valves being connected by a single stem for simultaneous operation, with one pair forming an inlet valve for fluid under pressure, and another pair controlling the discharge of the fluid under pressure from the tube, a connected float and weight being actuated by the rise and fall of the liquid in the tube for controlling the opening of one pair of the valves and for causing simultaneous closing of the other pair of valves and vice versa.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawing:

Figure 1 is a vertical section of the fluid pressure pump constructed in accordance with the principles of my invention,

Figure 2 is an enlarged fragmentary vertical section showing the valve mechanism, and

Figure 3 is a horizontal section taken along the line 3—3 of Figure 2.

In the production of crude petroleum the wells usually start producing by a natural flow due to high gas pressure and volume in the producing sand. When the gas pressure and the volume decrease sufficiently some artificial means must be employed to assist in the lifting of the oil. In this event air or gas is introduced into the well which decreases the specific gravity so that the natural gas pressure of the well is sufficient to cause the column of mixed oil and gas to be elevated without the necessity of employing

a pump. However, the natural gas pressure decreases and it is necessary to employ some additional means other than the air lift method. The compressor equipment which has been previously utilized for impregnating the oil with a determined quantity of air to decrease the specific gravity of the oil may be employed for the operation of a pneumatic pump. However, where it is necessary to place the plunger pump, and which is frequently the custom, near the bottom of the well, the use of a pneumatic pump would be of little use.

In deep wells commonly drilled with rotary tools, the holes are usually so crooked that the rods frictionally engage the tubing and wear holes through the tubing, thereby weakening the rods to such extent that the tremendous strain of pumping against a head of several thousand feet of oil causes such rods to break. Furthermore, it is extremely difficult to pump large quantities of oil with a plunger type pump under these conditions.

In carrying out my invention I employ fluid pressure which is directed against the head of the oil in a tube 10 mounted in a section 11 of a string of tubing. The tubing 10 and casing 11 are sunk below the surface of the earth until they reach the usual sand pockets 12. The tube 10 is closed, as shown at 13, at its inner end, and is provided with a central passage 14 through which is inserted a discharge tube 15. The upper end of the tube 10 is closed, as shown at 16, while the section 11 extends beyond the closed end of the tube 10.

The discharge tube 15 is provided with openings 17 which place the discharge pipe in communication with the tube 10. A foot valve, generally designated by the numeral 18, is located in the pipe 15 below the bottom 13 of the tube 10. A second foot valve 19 is located in the pipe 15 and above the closed bottom 13 of the tube so that oil may pass the foot valve 18 and be discharged through the passages 17 of the pipe 15 where it enters the tube 10. The valve 19 will permit the liquid forced through the tube 10 to be elevated in the pipe 15 but will prevent the liquid from returning to the tube. In like manner the valve 18 will prevent the liquid from pipe 15 and tube 10 from passing back into the well.

An elongated float 20 is slidably mounted on the pipe 15 and is received within the space between the said pipe and the tube 10. A

weight 21 is slidably mounted in the tube 10 and is ring-shaped and is of such a thickness that it may freely pass the float 20 as will be presently explained. Cables or chains 22 connect the ring-shaped weight 21 with the float 20 and these cables are trained over pulleys 23 secured to the inner face of the tube 10 adjacent the upper end thereof.

An inlet valve casing 24 is connected with a short length of pipe 25 which extends through the partition or top 16 of the tube 10 and is adapted to place the tube in communication with the valve casing. A conduit 26 is connected to the top of the valve casing 24 and also with a source of compressed air or gas (not shown). The valve casing 24 has a partition 27 which cuts off communication between the pipe 26 and the casing 24. A by-pass 28, however, is employed for connecting the valve casing 24 above the partition 27 with the interior of a valve cage 29 and at a point between a pair of valves 30 and 31. It will be noted that these valves are similarly formed and are moved to outer or closed position to engage their respective seats 32 and 33. A stem 34 connects the valves 30 and 31 for simultaneous operation.

The discharge valve is provided with a casing 40 which is placed in open communication with the tube 10 by means of a pipe 41. The upper end of the casing, as shown at 42, is open to the atmosphere or to the upper end of the casing 11. A valve cage 43 is mounted within the casing 40 and is provided with a pair of seats 44 and 45 adapted to be engaged, respectively, by valves 46 and 47. A stem 48 connects the pair of valves for simultaneous operation. A by-pass 49 has a port 50 opening into the upper end 42 of the casing 40 and a port 51 opening into the valve cage between the valves 46 and 47.

A lever 60 is pivotally mounted intermediate its ends, at 61, on the discharge pipe 15. One end of the lever is shown at 62 and suitably connected with the valve stem 42. The other end of the lever is shown at 64 and is pivotally connected with the valve stem 34. The lever at this point has an extension 65 for a purpose which will be presently explained. The stem 48 has an extension 66 located within the path of the upper end of the float 20 whereby said stem will be engaged by the float and moved to actuate the lever 60.

When the wells are of exceptional depth, or when it is necessary to impregnate the oil with a gas or air to decrease the specific gravity of said oil, a connection 80 may be provided for placing the conduit 26 in communication with the pipe 15 so that as the oil passes the connection 80 air or gas will be forced through the same and will act as an air lift as is well known.

The operation of my device is as follows: The float 20 is being elevated, as shown in Fig. 1, by the rise of the liquid in the tube 10

which has been normally forced upwardly through the pipe 15 and into the tube 10 by the gas pressure in the well. When the float is raised sufficiently it will engage the extension 66 of the stem 48, forcing the stem upwardly and moving the valves 46 and 47 on their respective seats and thus closing the tube 10 to the atmosphere or to the upper end of the casing 11. When the stem is moved upwardly the lever 60 is actuated, causing the extension 65 of said lever to be moved downwardly and thereby forcing the valves 30 and 31 from their respective seats. At this time air or gas under pressure, which is in the pipe 26, is admitted to the top of the tube 10 and acts on the head of the oil in said tube, forcing same downwardly. The valve 18 prevents the oil from returning through the well and is, therefore, elevated in the pipe 15 and discharged out of the upper end where it is collected and placed in storage.

When the level of the oil in the tube 10 is forced downwardly the weight of the float 20 is sufficient to cause the same to descend and elevate the weight or member 21. At the uppermost limit of movement of said ring it engages the extension 65 of the lever 60, forcing the same upwardly and causing the stem 34 to close the valves 30 and 31. The opposite action of the valves 46 and 47 takes place. This is due to the fact that elevation of the extension 65 of the lever 60 causes a lowering of the opposite end, thereby moving the stem downwardly causing the valves 46 and 47 to be moved away from their seats. However, when the pressure of the fluid from the conduit 26 is relieved in the tube 10, the natural pressure of the gas from the oil well will cause the oil again to rise in the tube 10 and pipe 15. At this time the float 20 will be elevated until it reaches the point where it engages the stem 66 and thus cause the valves 46 and 47 to be closed while the valves 30 and 31 will be open.

It will be particularly noted that the by-pass 28 in the valve casing 24 causes the compressed fluid from the pipe 26 to enter the space in the valve cage 29 at a point between the valves 30 and 31 so that the pressure on these valves will be balanced and only a slight pressure is needed to remove them from their seats. Thus the weight of the float 20 will be sufficient to cause the ring 21 to be elevated and release the valves 30 and 31 from their seats. The by-pass 49 places the valve cage 43 in communication with the atmosphere at a point between the valves 46 and 47 so that atmospheric pressure is balanced on both valves and in opposite directions, so that when the valves 30 and 31 are closed, the valves 46 and 47 may be readily opened and vice versa.

I claim:

1. A fluid pressure pump comprising a tube, a discharge pipe for liquid disposed

7. A fluid pressure pump comprising a tube, a discharge pipe for liquid disposed centrally within the tube and in open communication at the lower end with the tube, means for sealing the tube intermediate the ends thereof, a balanced valve structure including a pair of valves and a stem connecting the valves for simultaneous actuation and providing a discharge for fluid from the tube past the sealing means, a conduit for supplying a fluid under pressure to the tube, a balanced inlet valve structure including a pair of valves and a stem connecting the valves for simultaneous actuation for controlling the flow of fluid into the tube, means actuated by the rise

and fall of the liquid in the tube for causing closing of one pair of valves and opening of the other pair of valves, the fluid pressure acting on the liquid in the tube for forcing the liquid through the discharge pipe, a by-pass connecting the fluid supply conduit with the inlet valve structure and opening between the pair of valves, and a by-pass connecting the valves with the atmosphere at a point between said valves. 20

Signed at Tulsa, in the county of Tulsa and State of Oklahoma, this 23rd day of January A. D. nineteen hundred twenty-eight. 25

FORREST E. GILMORE.
